UNITED STATES PATENT OFFICE

158,647

ACCOUNTING MACHINE

Thomas M. Butler, Detroit, Mich., assignor to
Burroughs Adding Machine Company, Detroit,
Mich., a corporation of Michigan

Application November 17, 1949, Serial No. 6,092

Term of patent 14 years

(Cl. D64—11)

To all whom it may concern:

Be it known that I, Thomas M. Butler, a citizen of the United States, residing at Detroit, county of Wayne, State of Michigan, have invented a new, original, and ornamental Design for an Accounting Machine, of which the following is a specification, reference being had to the accompanying drawing, forming a part thereof.

In the drawing:

Figure 1 is a front perspective view of an accounting machine showing my new design; and
Fig. 2 is a rear perspective view thereof.

I claim:

The ornamental design for an accounting machine, substantially as shown.

THOMAS M. BUTLER.
